(57) **CLAIM**

The ornamental design for medical device handle, as shown
and described.

DESCRIPTION

The file of this patent contains at least one drawing executed
in color. Copies of this patent with color drawings will be
provided by the United States Patent and Trademark Office
upon request and payment of the necessary fee.

FIG. 1 is a front perspective view of medical device handle
illustrating our new design;

FIG. 2 is an enlarged front side view thereof;

FIG. 3 is an enlarged back side view thereof;

FIG. 4 is a left side view thereof;

FIG. 5 is a right side view thereof;

FIG. 6 is a top view thereof; and,

FIG. 7 is a bottom view thereof.

The portions of the device shown in broken lines form no
part of the claimed design. The uncolored portions of the
device enclosed by broken lines form no part of the claimed
design.
